(74) *Attorney, Agent, or Firm* — Norton Rose Fulbright US LLP

(57) **CLAIM**

The ornamental design for a stand top, as shown and described.

DESCRIPTION

FIG. 1 is a top view of a stand top showing my new design; and,

FIG. 2 is a front view thereof, the views after rotating the stand 120 degrees in either direction about a longitudinal axis that is centered within and extends through the stand's top, from top to bottom, being identical.

The shape of the stand top showing my new design is symmetrical about each of three planes that are positioned: (a) at 120 degree angles to each other, and (b) perpendicular to the sheet depicting FIG. 1, where one of the planes bisects equally the left and right sides of the stand top in FIG. 1. Each of the three side surfaces that meets the top surface of the stand top along an edge is planar.

The stand top is intended to be part of a stand placed on a tray and used as a support for the tray cover and possibly one or more stacked trays, for items such as edible items.

The broken lines showing portions of the stand top in the figures are for the purpose of illustrating environmental structure only and form no part of the claimed design.

1 Claim, 2 Drawing Sheets
